UNITED STATES PATENT OFFICE.

ELLIS W. COOPER, OF BLOOMFIELD, NEW JERSEY, ASSIGNOR TO R. HOE AND CO., OF NEW YORK, N. Y., A CORPORATION OF NEW YORK.

BEARERS.

1,140,254.

Specification of Letters Patent. Patented May 18, 1915.

Application filed August 26, 1913. Serial No. 786,668.

To all whom it may concern:

Be it known that I, ELLIS W. COOPER, a citizen of the United States, residing at Bloomfield, county of Essex, and State of New Jersey, have invented certain new and useful Improvements in Bearers, fully described and represented in the following specification and the accompanying drawings, forming a part of the same.

10 This invention relates to bearers or bearing bands for use with printing machines. In many classes of printing machines that are employed for producing fine work, it is desirable that the cylinders, turning rolls, 15 pipe rolls, etc. over which the printed surface of the sheet or web runs should be provided with portions where the margin of such sheet or web can be raised above the remaining portion of the cylinder or roll, 20 so that the printed portion of the sheet or web is kept out of contact with the roll, and blurring thereby prevented while the sheet after receiving its impression is being conducted to other mechanisms, such as slitters, 25 etc. As the width of the sheet or web varies, however, from time to time, it is necessary that such raised portions be of such character as to be adjustable to different positions along the cylinder. Various devices 30 for effecting this have been suggested. That generally heretofore used has been to provide thin bands of copper or steel held by spring pressure, these bands encircling the cylinder at suitable points on its periphery, 35 and adjustable along the surface of the cylinder. Due to the fact that these bands have to be very thin to prevent breaking of the web, difficulty has been experienced in their use due to the fact that they become dis- 40 torted and do not maintain their shape after they have been thus adjusted a few times.

It is the especial object of the present invention to provide an improved bearer which preferably is in the form of an endless band 45 or belt of flexible material, as webbing or soft metal, and so supported that it may be tightened to bring it in correct position with relation to the periphery of the cylinder, and at the same time readily loosened so as 50 to be moved along the cylinder without warping or otherwise altering its shape, so that it will efficiently effectuate the functions for which it is intended.

For a full understanding of the invention, 55 a description will now be given of certain

constructions embodying the same, taken in connection with the accompanying drawings, in which—

Figure 1 is a diagrammatic side elevation of part of a printing machine showing a bending or turning roll and a pair of slitting rolls operating on a web; Fig. 2 is a side view of a hollow roll partly broken away showing certain of the improved bearers in position; Fig. 3 is a longitudinal section on an enlarged scale showing a bearer and the preferred method of supporting the same; Fig. 4 is a cross section taken on line 4—4 of Fig. 3; Fig. 5 is a cross sectional view taken on line 5—5 of Fig. 6 showing a modification which may be employed when used with cylinders or rolls provided with interior shafts, and Fig. 6 is a side view partly broken away and partly in section of the modified construction illustrated in Fig. 5.

Referring now to the drawings, it will be understood that the improved bearer is intended for use with those rolls and cylinders over which the printed sheet passes after receiving its impression. Such rollers may be cylinders, bending or turning rolls, pipe rollers, guide rollers, etc., and the invention has been illustrated in one of its forms as shown in connection with a bending or turning roll for turning or directing a web to slitting mechanism. As shown in the drawings, this roll is marked 1, and the slitting rolls 2, 3 to which the web W is guided by the roll are shown in conjunction therewith.

Bearers constructed in accordance with the invention comprise strips or belts of flexible material, webbing being preferred, and in the preferred form, these strips or belts are endless, the ends being suitably secured together as by sewing. If desired, however, endless strips of soft metal may be employed. The bearers 4 are mounted so that they may be brought into close relation with the outer periphery of the cylinder with which they are employed, and at the same time so that they can be loosened and moved along the periphery of the cylinder without deforming them or altering their shape. The means for mounting the bearers to effect this may be widely varied. In the particular construction illustrated the bearer is supported and held from within the cylinder or roll, which is provided at

- suitable points on its periphery with elongated slots 5 through which the bearer passes, these slots being of a length sufficient to permit the bearer to be moved along the 5 periphery of the cylinder the distance desired for the varying sized sheet or web which is being produced.
- Positioned within the cylinder is a support. This support may be varied in construction. Where the cylinder or roll is a hollow one, this support may be in the form of a bar 7 which is dimensioned to be passed through the slots 5 before referred to when assembling the parts. This bar 7 is provided 10 at each end with threaded bosses 8 into which take set screws 9. These set screws are preferably, in the best constructions, provided with springs 10 which take between the bosses 8 and the inside wall of the cylinder or roll. The bearer, which in the particular construction illustrated, is an endless belt of webbing, is looped under this bar, as shown in Fig. 4, passing through the slot 5 around the outer periphery of the 15 cylinder. It is apparent that by screwing up on the set screws 9 the bar will be drawn inwardly and the webbing tightened on the outer periphery of the cylinder. When it is desired to shift the bearer, it is simply 20 necessary to loosen the set screws 9, when the supporting bar, by the action of the spring 10, will loosen the webbing sufficiently to permit it to be slid to the desired point on the periphery of the cylinder. By 25 this construction, the bearers may be easily adjusted without in any way becoming deformed or losing their shape, and thereby becoming ineffective for the purpose for which they are employed.
- 40 In many instances, it is desirable, in printing press constructions, that the cylinders, rolls, etc., should be mounted to rotate on a shaft passing therethrough. In Figs. 5 and 6 is illustrated a construction of simple devices, whereby the improved bearers may be used with cylinders and rolls so mounted, and in which are illustrated two bearers carried by one supporting device, the bearers 4, which are or may be endless bands of webbing, being looped about a supporting rod or bar 12. This supporting bar is held by means of suitable set screws 13 in rings 14 which encircle the cylinder shaft 15 and clear the shaft by a space sufficient to give 45 the necessary loosening and tightening movement to the bar or rod 12. These rings 14 are provided with bosses 16 into which take set screws 17, springs 18 being provided between the bosses and the inner periphery or 50 inner wall of the cylinder. By taking up or loosening the set screws 17 the rings, and with them the bar, may be adjusted sufficiently to tighten the belt to bring it in close contact with the outer periphery of the 55 cylinder or may be loosened sufficiently to

enable the belt to be slipped or slid along the cylinder to the position desired. With the construction shown in Fig. 6 two of the bearers are supported by one supporting rod, by adjusting which both bearers may be 70 loosened or tightened up at the same time.

While a convenient means has been shown and described for supporting the bearers so they may be suitably adjusted, it will be understood that the invention is not to be restricted to such means, but that certain changes and variations may be made in the same without departing from the invention.

What is claimed is:

1. The combination with a hollow roll, of 80 a plurality of supporting bars located within the roll, a plurality of endless flexible bands, one for each support, looped under the support and passing around the periphery of the roll at different points thereon, 85 and means whereby the supports may be adjusted for tightening or loosening the bands so that the bands may be moved to varying positions along the roll.

2. The combination with a hollow roll provided 90 with a peripheral slot, of a supporting bar located within the roll, an endless band of webbing looped under the bar and passing through the slot around the outer periphery of the roll, set screws by which 95 the supporting bars may be adjusted to tighten or loosen the band of webbing so that it may be moved to varying positions along the roll, and springs between the supporting bar and the inner wall of the roll. 100

3. The combination with the cylinder of a printing machine, of a plurality of bands of flexible material substantially encircling the periphery of the cylinder and spaced from each other the width of the printed 105 matter on a sheet, and supporting devices located within the cylinder for tightening and loosening the bands about the cylinder.

4. The combination with the cylinder of a printing machine, of a plurality of bands of 110 flexible material substantially encircling the periphery of the cylinder spaced from each other the width of the printed matter on a sheet and adjustable to varying positions along the cylinder surface, and supporting 115 devices located within the cylinder for tightening and loosening the bands about the cylinder.

5. In combination with the cylinder of a printing machine, a plurality of margin 120 bearers spaced from each other the width of the printed matter on a sheet, said bearers each including a band of flexible material substantially encircling the periphery of the cylinder and coöperating with a suitable 125 support located within the cylinder, the said support being movable to tighten or loosen the band about the cylinder.

6. In combination with the cylinder of a printing machine, a plurality of margin 130

bearers spaced from each other the width of the printed matter on a sheet, each bearer including a band of flexible material substantially encircling the periphery of the cylinder and passed under a suitable support located within the cylinder and movable to varying positions along the cylinder surface.

In testimony whereof, I have hereunto set my hand, in the presence of two subscribing witnesses.

ELLIS W. COOPER.
